DOMESTIC APPLIANCE

George B. Long, Dayton, Ohio, assignor to General Motors Corporation, Detroit, Mich., a corporation of Delaware

Application March 8, 1956, Serial No. 570,317

7 Claims. (Cl. 312—296)

This invention relates to a domestic appliance and more particularly to double doors for electronic ovens and other compartments.

In electronic ovens, it is essential to prevent arcing between metal surfaces in the field of electromagnetic waves and also to prevent the escape of electromagnetic waves from the oven. This is particularly a problem when double doors are provided for closing the oven compartment.

It is an object of this invention to provide a wall type oven with double doors making a tight metal to metal seal with each other and with the walls of the oven for preventing arcing and the escaping of electromagnetic waves. It is another object of this invention to provide a wall type oven with double doors in which the meeting faces of the doors are always properly aligned in closed position.

These and other objects are attained in the form shown in the drawings in which the wall type oven is provided with a magnetron tube cooled by a blower which also rotates the mode stirrer in the top of the oven. An electric fan draws air from the room around the magnetron tube and the wave guide and the electronic apparatus, and returns the warmed air to the room. The oven is provided with double doors having inner movable panels which are slidably mounted in a lateral direction. When the doors are closed one set of springs urges both inner panels tightly against the portion of the walls surrounding the front opening to the oven while a second set of springs urges the panels together at their adjacent edges. In one form of the invention movable handles are provided, either of which will move the one inner panel toward the hinges and hold it in that position until the door is reclosed to insure that both panels will be held tightly against the portion of the wall surrounding the opening of the oven compartment before the panels move into contact with each other.

In another form the meeting edges of the panels are provided with matching abutting surfaces to assure the alignment of the inner faces of the panels when the doors are closed so that both panels will be held by the springs in reasonable tight engagement with the portion of the wall seal at the opening to the oven compartment. Further objects and advantages of the present invention will be apparent from the following description, reference being had to the accompanying drawings, wherein a preferred form of the present invention is clearly shown.

In the drawings:

Figure 1 is a vertical sectional view through a wall type oven provided with double doors embodying one form of my invention;

Figure 2 is a rear view of the doors shown in Figure 1;

Figure 3 is a fragmentary sectional view of the doors taken along the line 3—3 of Figures 1 and 2;

Figure 4 is a fragmentary sectional view similar to Figure 3 with the doors shown partly open; and

2

Figure 5 is a fragmentary sectional view similar to Figure 3 but showing a modified form of the panel matching arrangement.

Referring now to the drawings and particularly to Figure 1, there is shown an electronic oven arrangement 20 mounted in a vertical wall 22. This electronic oven arrangement 20 includes an outer casing formed of top, bottom, side and rear walls 24. Within this casing 24 is mounted an oven liner 26 immediately enclosing the electronic oven compartment 28. The space between the casing 24 and the oven liner 26 provides a passageway 30 containing an electronic apparatus 32 which provides a suitable supply of energy to the magnetron tube 34 cooled by the blower 36 driven by the electric motor 38. The shaft of the motor 38 is also provided with a pulley 40 which through a belt 42 and a second pulley 44 drives the mode stirrer 46 within the top of the oven compartment 28. Beneath the stirrer 46 is a sheet of quartz 48 or similar material which will pass electromagnetic waves and withstand heat. This sheet 48 shields the stirrer 46 from the sputtering of the grease during broiling.

The magnetron tube 34 delivers electromagnetic waves through the wave guide 50 through an opening 52 in the top of the oven compartment 28. These electromagnetic waves are uniformly distributed throughout the compartment 28 by the stirrer 46. The apparatus is further cooled by an electric motor driven fan 54 which draws in air through the upper inlet 56 into the passage 30 into heat exchanger relation with magnetron tube 34 and the electronic apparatus 32 and discharges the air through a louver or grille 58 located in the front end of the lower leg of passage 30 beneath the double doors 60 and 62. The oven compartment may be provided with a resistance heater 64 for broiling and browning certain food. Suitable screened openings 66 in the liner and 68 and 70 in the doors 60 and 62 are provided. These openings 66, 68 and 70 have screens of sufficiently small mesh to prevent the escape of electromagnetic waves but permit the escape of vapors and fumes, and permit viewing the food load as it is cooked.

As shown in Figure 2 the doors 60 and 62 on their inner face are provided with inturned flanges 72 and 74 upon the top and bottom and the hinged edges. These flanges 72 and 74 limit the inward movement of the inner panels 76 and 78 as well as the movement of the panels 76 and 78 toward the hinges 80. As best shown in Figures 3 and 4 the panels 76 and 78 of thin flexible metal are resiliently urged outwardly by leaf spring members 82 and 84 which are located at various points within the doors so as to provide a substantially uniform force holding the panels 76 and 78 against the flanges 72 and 74 when the doors 60 and 62 are in the open position. When the doors are closed, these springs hold the panels 76 and 78 against the formed flat faced bead 86 which extends around the front face of the door jamb 88 immediately surrounding the access opening to the oven compartment 28. Preferably, these panels are of .015" stainless steel which readily conforms to any irregularities of the bead 86.

The panels 76 and 78 are not only mounted so as to be movable forwardly and rearwardly but they are also permitted lateral movement by the flanges 72 and 74. The meeting edges of the panels 76 and 78 are provided with meeting flanges 90 and 92 which may include stiffening flanges 94 and 96. The panels 76 and 78 are resiliently urged toward each other by the laterally acting leaf springs 98 and 121 extending between the meeting flanges 90 and 92 and the inturned flanges 123 and 125 extending from the outer sheets 127 and 129 of the doors 60 and 62. This insures that the flanges 90 and 92 are held tightly in contact when the doors are closed.

Preferably the doors are each pivotally connected to the links 131. These links 131 are preferably pivotally connected at their opposite ends to each other and to a traveler 133 which is slidably mounted in a horizontal guideway 135 beneath the oven liner 26. This link and traveler arrangement insures that the doors are closed simultaneously and that the opening of either door will cause the simultaneous opening of the other door.

To insure that the faces of the panels 76 and 78 are always aligned when the doors are closed as shown in Figure 3, the doors 60 and 62 are provided with the movable door handles 137 and 139 which are pivotally mounted upon the outer panels 127 and 129. An inwardly extending pin 141 is connected to the handle 137 and a corresponding inwardly extending pin 143 is connected to the handle 139. These pins 141 and 143 are respectively adapted to engage the followers 145 and 147 which are fixed respectively to the panels 76 and 78. The follower 145 is provided with a projection 149 adapted to engage a projection 151 connected to the inner face of the outer panel 127 so as to hold the inner panel 76 from movement away from its hinged edge after it has been moved toward the hinged edge by the engagement of the pins 141 with the follower 145. In the opposite door the follower 147 is provided with a projection 153 which is similarly adapted to engage a corresponding projection 155 when the panel 78 is moved toward the hinge by the pin 143. Where the construction is such that the friction between the flanges 90 and 92 is small in the closing positions, the handle actuating system may be omitted.

The purpose of this handle arrangement is to make use of the pull upon either of the handles 137 and 139 when the door is opened to hold the meeting flanges 90 and 92 apart until after the doors are closed. The panels 76 and 78 firmly engage the bead 86 and the springs 82 and 84 are compressed sufficiently to allow the projections 149 and 153 to pass outwardly of the projections 151 and 155 to free the panels 76 and 78 to permit the meeting faces 90 and 92 to move together under the force of the springs 98 and 121 as shown in Figure 3.

In Figure 5 there is shown a modified form of the invention in which the doors 260 and 262 have inner panels 276 and 278 with concave and convex matching contacting flanges 290 and 292. These matching flanges 290 and 292 insure the alignment of the panels 276 and 278 when the doors 260 and 262 are moved into closed position against the bead 85. These panels 276 and 278 are similarly pressed against the bead 86 by the sets of springs 282 and 284. These panels 276 and 278 are also spring pressed toward the meeting edges by the laterally acting springs 298 and 321. These doors are provided with fixed handles 237 and 239 connected to their outer faces. They are also provided with flanges similar to the flanges 74 and 72. In all the door constructions, the inner panels float excepting for the restraint provided by the flanges 72 and 74 as well as the various springs and the followers 145 and 147.

The liner 26 and the door jamb particularly including the bead 86 are coated with porcelain enamel of the grade used for oven liners. The porcelain coating upon the door jamb and the bead 86 further prevents or further minimizes any tendency to establish an arcing condition between the bead 86 and the springy stainless steel panels 76 and 78. The porcelain coating tends to form an effective electrical insulation barrier between the metal of the door jamb and the liner 26 and the tightly contacting metal panels 76 and 78. This arc suppressing phenomena may be the result of the condenser-choke configuration formed by this design. The dielectric loss in the porcelain also tends to diminish to a negligible amount any electromagnetic radiation tending to escape between the bead 86 and the panels 76 and 78. This arrangement is also suitable when

infra-red heating or convection heating is used in the oven in combination with the micro-wave heating apparatus. The doors 60 and 62 may be filled with glass or mineral wool for preventing the escape of heat generated by the heater 64.

While the form of embodiment of the invention as herein disclosed constitutes a preferred form, it is to be understood that other forms be adopted, as may come within the scope of the claims which follow.

What is claimed is as follows:

1. In combination, walls enclosing a compartment, said walls having an opening therein providing access to said compartment, a set of doors having common meeting edges for closing said opening, pivotal connections pivotally connecting said doors adjacent the edges opposite said meeting edges to said walls, said doors each having inner movable panels and spring means for resiliently urging said panels into contact with said walls around said opening, one of said doors being provided with a lateral slideway for slidably supporting its panel, said panels having common meeting edges, said one door having spring means for resiliently urging its panel toward the meeting edge of the panel of the adjacent door.

2. In combination, walls enclosing a compartment, said walls having an opening therein providing access to said compartment, a set of doors having common meeting edges for closing said opening, pivotal connections pivotally connecting said doors adjacent the edges opposite said meeting edges to said walls, said doors each having inner movable panels and spring means for resiliently urging said panels into contact with said walls around said opening, one of said doors being provided with a lateral slideway for slidably supporting its panel, said panel having common meeting edges, said one door having spring means for resiliently urging its panel toward the meeting edge of the panel of the adjacent door, and means for aligning the common meeting edges of said panels when the doors are closed.

3. In combination, walls enclosing a compartment, said walls having an opening therein providing access to said compartment, a set of doors having common meeting edges for closing said opening, pivotal connections pivotally connecting said doors adjacent the edges opposite said meeting edges to said walls, said doors each having inner movable panels and spring means for resiliently urging said panels into contact with said walls around said opening, one of said doors being provided with a lateral slideway for slidably supporting its panel, said panel having common meeting edges, with matching surfaces, said one door having spring means for resiliently urging the panel toward the meeting edge of the panel of the adjacent door.

4. In combination, walls enclosing a compartment, said walls having an opening therein providing access to said compartment, a set of doors having common meeting edges for closing said opening, pivotal connections pivotally connecting said doors adjacent the edges opposite said meeting edges to said walls, said doors each having inner movable panels and spring means for resiliently urging said panels into contact with said walls around said opening, one of said doors being provided with a lateral slideway for slidably supporting its panel, said panels having common meeting edges, said one door having spring means for resiliently urging its panel toward the meeting edge of the panel of the adjacent door, a handle for opening one of the doors, and means operated by said handle for moving the panel of one of the doors away from the common meeting edge.

5. In combination, walls enclosing a compartment, said walls having an opening therein providing access to said compartment, a set of doors having common meeting edges for closing said opening, pivotal connections pivotally connecting said doors adjacent the edges opposite said meeting edges to said walls, said doors each having inner movable panels and spring means for resiliently

urging said panels into contact with said walls around said opening, one of said doors being provided with a lateral slideway for slidably supporting its panel, said panels having common meeting edges, said one door having spring means for resiliently urging its panel toward the meeting edge of the panel of the adjacent door, a handle for opening one of the doors, and means operated by said handle for moving the panel of one of the doors away from the common meeting edge, and stop means for holding the panel of one of the doors away from the common meeting edge when the handle is released.

6. In combination, walls enclosing a compartment, said walls having an opening therein providing access to said compartment, a set of doors having common meeting edges for closing said opening, pivotal connections pivotally connecting said doors adjacent the edges opposite said meeting edges to said walls, said doors having inner movable panels and spring means for resiliently urging said panels into contact with said walls around said opening, one of said doors being provided with a lateral slideway for slidably supporting its panel, said panels having common meeting edges, said one door having spring means for resiliently urging its panel toward the meeting edge of the panel of the adjacent door, a handle for opening one of the doors, and means operated by said handle for moving the panel of one of the doors away from the common meeting edge, and stop means for holding the panel of one of the doors away from the common meeting edge when the handle is released, said stop means being provided with a releasing arrangement operable coincidentally to the engagement of the walls around the access opening by the panel.

7. In combination, walls enclosing a compartment, said walls having an opening therein providing access to said compartment, a set of doors having common meeting edges for closing said opening, pivotal connections pivotally connecting said doors adjacent the edges opposite said meeting edges to said walls, said doors each having inner movable panels and spring means for resiliently urging said panels into contact with said walls around said opening, one of said doors being provided with a lateral slideway for slidably supporting its panel, said panels having common meeting edges, said one door having spring means for resiliently urging its panel toward the meeting edge of the panel of the adjacent door, a handle for opening one of the doors, and means operated by said handle for moving the panel of one of the doors away from the common meeting edge, a laterally extending projection connected to and movable with said panel, a second projection located in the lateral path of movement of said laterally extending projection at the termination of the movement of the panel by the handle, said second projection having a recess for disengaging said projections when the panel is deflected upon engaging the portion of the walls surrounding the door opening.
